US00D974276S

(12) United States Design Patent **(10) Patent No.:** **US D974,276 S**
Kooiman et al. **(45) Date of Patent:** **** Jan. 3, 2023**

(54) AIRCRAFT SPINNER

(71) Applicant: **Bell Helicopter Textron Inc.**, Fort Worth, TX (US)

(72) Inventors: **James E. Kooiman**, Fort Worth, TX (US); **Lynn F. Eschete**, Arlington, TX (US); **Kyle T. Cravener**, Watauga, TX (US)

(73) Assignee: **Textron Innovations, Inc.**, Providence, RI (US)

(***) Term: **15 Years**

(21) Appl. No.: **29/670,370**

(22) Filed: **Nov. 15, 2018**

(51) LOC (14) Cl. **12-07**

(52) U.S. Cl.

USPC **D12/345**

(57) CLAIM

The ornamental design for an aircraft spinner, substantially as shown and described.

DESCRIPTION

FIG. 1 is a front perspective view of an aircraft spinner shown with the environmental rotor nacelles facing forward; FIG. 2 is a front elevational view of the aircraft spinner in FIG. 1;

FIG. 3 is a rear elevational view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the aircraft spinner in FIG. 1 shown with the environmental rotor nacelles facing upward;

FIG. 9 is a front elevational view of the aircraft spinner in FIG. 8;

FIG. 10 is a rear elevational view thereof;

FIG. 11 is a right side view thereof;

FIG. 12 is a left side view thereof;

FIG. 13 is a top view thereof; and,

FIG. 14 is a bottom view thereof.

The broken lines illustrate environmental subject matter only and form no part of the claimed design.

1 Claim, 14 Drawing Sheets
